UNITED STATES PATENT OFFICE

92,194

DESIGN FOR A BATHROOM SCALE CASING

Harold I. Nicholas, Chicago, Ill.

Application February 27, 1934, Serial No. 50,895

Term of patent 3½ years

To all whom it may concern:

Be it known that I, HAROLD I. NICHOLAS, a citizen of the United States, residing at Chicago, in the county of Cook and State of Illinois, have invented a new, original, and ornamental Design for a Bathroom Scale Casing, of which the following is a specification, reference being had to the accompanying drawing, which is a perspective view of the article showing my new design.

I claim:—

The ornamental design for a bathroom scale casing, as shown.

In testimony whereof I affix my signature.
HAROLD I. NICHOLAS.
